UNITED STATES PATENT OFFICE

MERTON L. EMERSON, OF SYRACUSE, NEW YORK, ASSIGNOR TO THE LAMSON COMPANY, OF SYRACUSE, NEW YORK, A CORPORATION OF MASSACHUSETTS

METHOD OF AND APPARATUS FOR CONTROLLING AIR FLOW IN PNEUMATIC SYSTEMS

Application filed October 18, 1928. Serial No. 313,249.

This invention pertains to pneumatic despatch systems and relates more particularly to an improved method of and means for controlling the air flow in such a system.

5 Much effort has been expended in designing so-called "power control" apparatus for shutting off the flow of air, either by closing a valve or stopping the fan motor when the tube line is empty so that power will not 10 be wasted. Since it is undesirable to parallel the pneumatic tube line with cables, conduits, electric wires, or the like for actuating the power control means, and since it has commonly been thought necessary to

15 shut off the air flow whenever the last carrier emerged from the tube, either at the clerk's (sending) station or at the central (cashier's) station, resort has been had to apparatus of the so-called "minimum flow"

20 type wherein the entry of a carrier into the tube at either end produces a pressure variation in the tube operative to start the full air flow, and wherein discharge of the carrier at either end of the tube results

25 in cessation of carrier impelling flow through change in pressure or velocity of the air in the tube incident to such discharge. While the minimum flow type of control is practical and widely used, it 30 is very delicate in its construction and in its response to pressure variations, and requires frequent adjustment to keep it in satisfactory operation, particularly when the power control apparatus is installed in 35 situations where it is exposed to dust and dirt.

Careful study of the situation has convinced me that while it may be desirable from a theoretical standpoint to cut off the air flow whenever the tube line is empty (as by the discharge of a carrier at the cashier's as well as the clerk's station) this is not by any means necessary to economical operation as a practical matter. At the cashier's 40 or central station the operation of making change, authorizing charge accounts, etc. takes but a very short time, usually less than a minute, so that the interval between discharge of the carrier from the delivery terminal and the introduction into the despatch

terminal for return to the clerk's station is of comparatively short duration, and results in but little waste of power, it being remembered that during the transit of the carrier from and to the clerk's station, power 55 is necessarily expended in any system, and that even in the minimum flow type of apparatus there is a continuous flow of air, amounting to a substantial percentage of the full flow, in the intervals between trans- 60 sists of carriers.

On the other hand, the intervals between the despatch of carriers from the clerk's station are often of considerable duration, taking place in some installations or in certain store departments not oftener on the average than once an hour. Thus if means be provided at the clerk's station only for wholly cutting off the air flow in the intervals between successive transactions, results closely approximating those secured from usual power control apparatus (so far as economy and power is concerned) may 65 readily be obtained.

In accordance with the present invention, 75 the air flow through the tube line is maintained at its full value from the time the carrier is despatched until its return to the sending station and is then wholly cut off. Conceivably, the carrier impelling flow may 80 be initiated and stopped by the use of a manually actuated valve or switch at the sending station, but such an arrangement to be effective in the saving of power would require the attention of the clerk until the 85 return of the carrier. For this latter reason, I prefer to provide automatic means at the clerk's or sending station for starting and stopping the air flow. For this purpose I preferably take advantage of the fact that 90 a predetermined complement of carriers is normally assigned to each sending station, each carrier when despatched, returning to its point of origin, and provide control means responsive to the presence of an idle 95 carrier in or its absence from a predetermined position at the sending station so that whenever a carrier is absent from the control means (as for example during its despatch to the central station and its return) the 100

full carrier impelling air flow is maintained in the tube line, but that whenever there is a full complement of carriers at the sending station, the control means, responding to the presence of the carriers, cuts off the air flow completely. Preferably the control means responds to the weight of the carrier, although I contemplate other forms of control as within the scope of the invention.

10 The apparatus herein disclosed is of simple character as compared with most power control devices; it is relatively cheap to construct and install; it is positive in action and requires but little attention for repairs or adjustment, and under most conditions of installation results in a saving of power equivalent to, if not greater than, that obtained by the use of the much more expensive and troublesome systems heretofore employed.

20 In the accompanying drawings I have illustrated by way of example one desirable embodiment of the invention, it being understood that various changes in the shape, size and proportion of parts, and the substitution of equivalents may be made without departing from the spirit of the invention.

In the drawings:

20 Fig. 1 is a diagrammatic elevation to small scale, showing the invention embodied in a normal type of pneumatic tube line;

25 Fig. 2 is a side elevation of the improved terminal apparatus arranged for downward discharge of carriers, the parts being shown in inoperative position with the controlling valve closed;

30 Fig. 3 is a view similar to Fig. 2 but showing the controlling valve open;

35 Fig. 4 is a front elevation of the apparatus shown in Figs. 2 and 3, omitting the controlling valve and adjacent parts of the tube;

40 Fig. 5 is a vertical section to larger scale substantially on the line 5—5 of Fig. 4;

45 Fig. 6 is a fragmentary bottom plan view, partly in section substantially on the line 6—6 of Fig. 5;

50 Fig. 7 is a side elevation showing terminal apparatus similar to that of Fig. 2 but arranged for upward discharge of carriers; and

55 Fig. 8 is a section to larger scale substantially on the line 8—8 of Fig. 7, showing details of a desirable form of closure for a carrier despatch opening.

Referring to the drawings and particularly to Fig. 1, I have indicated diagrammatically a pneumatic tube 1 leading from the clerk's or sending station 2 to the central of cashier's station 3. At the cashier's station this tube is connected in usual manner to means for producing carrier impelling air flow in the line, such for example as a pump or the vacuum tank 4. The tube 1 is

furnished with a delivery opening normally closed by means of a valve 4 in the usual manner. From the cashier's station a tube 6 extends back to the clerk's station 2, the receiving or despatch end 7 of the tube 6 being normally open at the cashier's station.

70 In accordance with the present invention, I provide a tube terminal comprising a normally closed and substantially air-tight box of sheet metal or other suitable material at the clerk's station. This box is provided at its front side, or sides, with an opening 9 (Fig. 5) through which carriers may be inserted and removed. This opening is normally closed by means of a door 10, hinged at 11, and provided with a handle 12. A spring 13, or an equivalent weight, tends to swing the door to closed position, and during the transmission of carriers through the pneumatic line the door is held firmly closed in air-tight engagement with the edges of the opening by atmospheric pressure acting upon its outer side. Any suitable packing material, for example a strip 14 of felt, or rubber, may be interposed between the door and the wall of the casing to ensure an air-tight joint.

75 Arranged vertically in the rear part of the box is a substantially vertical tubular guide 15 secured firmly in position by solder or other suitable connection, and projecting above and below the box. The lower projecting portion 15^a of the tubular guide is adapted to be connected to the tube 6 leading from the cashier's station by means of a sleeve 16 or other appropriate connecting element. In the arrangements shown in Figs. 2, 3 and 5 the upper end portion 15^b of the tubular guide which projects outside of the box 8, is closed by means of an air-tight cap 17.

80 The front part of the tubular guide 15 is cut away within the box as shown at 18 to provide an elongate opening through which carriers arriving through the tube may discharge into the interior of the box. I preferably provide deflector means 19, 19^a against the rear wall of the tube 15 adapted to cause carriers moving either upwardly or downwardly along the guide 15 to be diverted forwardly into the front of the box 8.

85 Within the box 8 I provide a false bottom 20 spaced from the bottom proper of the box and which preferably inclines downwardly and forwardly toward the lower part of the opening 9. This false bottom 20 is provided with an opening 20^a of sufficient size to permit the ready passage of carriers therethrough. Registering with this opening is the upper end of a tube 21 which leads downwardly through the bottom of the box 8 into a casing 22. Directly in line with the tube 21 leading from the casing 22, is a nipple 23 adapted to be connected by means of a sleeve 24 or other appropriate device to the

tube 1 leading to the cashier's station. The casing 22 is connected to or integral with a hollow part 25 providing a valve chamber within which is mounted a valve 26, here shown as of butterfly type, secured to a shaft 27, one end of which projects outwardly through the wall of the valve chamber. The upper part of the valve chamber is connected by means of a short pipe or nipple 28 to the interior of the box 8, the nipple 28 entering the bottom of the box 8 at a point near the edge of the false bottom 20. A guard member 20^b extends from the lower part of opening 18 in the tube 15 to the rear edge of the false bottom 20, such guard member being so designed as to prevent entry of a carrier beneath the false bottom while permitting free flow of air from the tube 15 to the nipple 28.

20 A lever 29 is fixedly secured to the end of the shaft 27 and at one end this lever is slotted for the reception of a pin projecting from the lower end of a rod 30 arranged to move vertically in guides as for example, a vertical bore in a boss 31 (Fig. 4) projecting from the box and a socket in a boss 32 in the upper part of the box. The rod 30 constitutes part of a rack comprising a series of cradle-like members 33, 33', 33², etc. each of 25 said cradle-like members being adapted to support a carrier, C, C¹, C², etc. The lever 29 is provided with an adjustable weight 34 which is normally adjusted so as to overbalance the weight of the rod 30, the rack carried thereby, and a series of carriers filling all but one of the cradles 33 so that the parts tend to assume the position shown in Fig. 3 with the valve 26 open. However, the adjustment of the weight is such that 30 when all of the cradles contain carriers, the weight 34 is overbalanced and the parts occupy the position shown in Fig. 2 with the valve 26 closed.

40 Preferably I provide a cover 34 normally closing the entrance 20^a to the tube 21, the valve 34 being connected to the door 10 by means of a link 35 pivotally attached to a lug 36 projecting from the inside of the door so that when the door 10 is swung 45 down to the dotted line position, Fig. 5, the cover 34 simultaneously opens so as to expose the entrance to the tube 21.

Near the rear end of the false bottom 20 I provide a transverse shaft 37 mounted in 50 brackets or other supports, and on this shaft I mount a swinging detector member 38. A spring 39 coiled about the shaft 37 tends to hold the detector 38 in the upper position indicated in Fig. 5. A rod 40, projecting rigidly downwardly from the detector 38 through an opening in the false bottom 20, engages an arm 41 (Fig. 6) of a lever device pivoted to swing on a pin 42 projecting downwardly from the false bottom 20. 55 This lever device has an arm 43 disposed

closely adjacent to the inner surface of the box 8 and carrying a valve pad 44 normally closing an aperture 45 in the wall of the box. Registering with this opening, at the outside of the box, is a whistle device 46 of such character that when the aperture 45 is open the suction or low pressure within the box will cause the whistle to sound.

In the modified arrangement shown in Figs. 7 and 8, the box, with its appurtenances including the valve and carrier supporting rack, is identical with that shown in the preceding figure, but in this instance it is arranged for use with an upwardly extending despatch tube. For the purpose, the lower end 15^x of the tubular guide 15 is closed by means of a cap 17' while its upper end is open and connected by means of the sleeve 16^a to the upwardly extending tube 6^a leading from the cashier's station. 60 Likewise a cap 22^a shown in Fig. 3 as closing an aperture in casing 22 is removed to permit attachment to the casing 22 of the lower end of the despatch tube 1 leading to the cashier's station, the lower end of the 65 nipple 23 being closed by a cap 22^b. In this instance the despatch tube 1^a is furnished with an opening 46^a for admission of a carrier, and this opening is normally closed by means of a door 47 mounted upon 70 a spring hinge at 48 which tends to keep the door closed, the door being provided with a handle 49. Any suitable packing means, if necessary, may be provided to ensure a tight joint between the door and the walls of the 75 tube.

The arrangements disclosed in Figs. 1 to 6 inclusive operate substantially as follows, it being assumed that the parts normally occupy the position shown in Fig. 2 with a full complement of carriers in the rack, the valve 26 and the door 10 being closed. When the clerk wishes to have a transaction performed at the central or cashier's station, he removes one of the carriers, for example the uppermost carrier C, (Fig. 2) 80 from the rack, and in the usual manner inserts in the carrier the currency, charge order, or other material to be transmitted to the distant station. In removing the carrier from the rack, the total weight of the rack is decreased sufficiently to permit the weight 34 to raise the rack with the remaining carriers, at the same time opening the valve 26 and thus permitting full carrier 85 impelling flow of air to enter the end 7 of the tube 6 and flow through the latter tube to the box, and thence through the nipple 28 past the open valve 26 and through the valve casing 22 into the pipe 1.

The operator now opens the door 10, simultaneously opening the cover 34 and exposing the open upper end of the tube 21. The carrier is now inserted in the tube 21 and drops by gravity through the casing 130

22 and the nipple 23 into the pipe 1 where it is swept onwardly by the air current and carried to the cashier's station. As soon as the carrier has been inserted in the tube 5 21, the door 10 is closed, thus closing the opening leading into the tube 21, but without affecting the flow of air current since the air is free to pass through the guard 20^b into the valve casing 22. When the proper 10 transaction has been performed at the cashier's station, the carrier is inserted in the open end 7 of the tube 6 and is impelled by the flowing air current through the latter tube to the clerk's station where it enters 15 the box upwardly through the tubular guide 15 and is diverted by the deflector 19 toward the forward part of the box, where it falls upon the deflector member 38. The weight of the carrier depresses the deflector 20 member and through the pin 40 swings the lever arm 43 so as to remove the pad 44 from the opening 45. At this time the suction is still maintained within the box and thus air is drawn inwardly through the 25 whistle 46, causing the latter to sound, thus notifying the clerk that a carrier has arrived in the box. The clerk now opens the door 10 and removes the carrier, thus permitting the deflector 38 to resume its normal 30 position, whereupon the whistle ceases to sound. The clerk removes the contents from the carrier and places it in the proper cradle of the rack causing the rack to descend, thus raising the weight 34, closing the valve 26, and restoring the parts to normal 35 position wherein flow of air through the tube line is completely cut off.

In describing the above sequence of operations it is assumed that but a single 40 carrier is removed from the rack at one time, but if more than one carrier be removed and transmitted to the cashier's station it is obvious that the valve 26 will remain open until all of the carriers which 45 have been despatched have been returned and replaced in the rack.

The apparatus thus provides automatic means for completely cutting off air flow in the tube line leading to any given sending station, whenever such tube line is idle that is to say when all of the carriers assigned to such station are idle and in readiness at the station for use. On the other hand, the apparatus automatically opens 50 the valve to permit carrier impelling air flow whenever a carrier is put into use and maintains a full air flow until such time as the carrier or carriers have returned to the sending station.

60 The arrangements shown in Figs. 7 and 8 operate in substantially the same way as that above described except that in despatching a carrier to the door 47 is opened and the carrier placed within the upwardly 65 extending tube 1^a leading to the cashier's

station. When this door is closed the air current admitted through the open valve passes through the casing 22 and into the tube 1^a, thus driving the carrier forward to the cashier's station. When the carrier is returned it is received through the pipe or tube 6^a and passes downwardly into the box, being deflected by the member 19^a 70 toward the forward part of the box so that it comes to rest on the deflector 38 and operates the signal as above described. 75

While a whistle forms a desirable form of signal, it is obvious that other types of signal, for example electrically actuated lamps, bells, etc. may be employed. It is further contemplated that various changes 80 in the shape, arrangement, and function of parts and the substitution of equivalents fall within the scope of the invention.

I claim:

1. Power control apparatus for use with a pneumatic tube line extending between two stations, said apparatus comprising a substantially air-tight box having a normally closed door, and connections secured to the box adapting it to form a receiving terminal alternatively for upwardly or downwardly extending pneumatic tubes. 85 90

2. Power control apparatus for use with a pneumatic tube line extending between two stations, said apparatus comprising a substantially air-tight box having a normally closed aperture in its front wall, a tubular guide extending through the box and having portions projecting from both the top and bottom of the box and adapted respectively for connection alternatively to downwardly or upwardly extending delivery tubes, and means for closing the inactive end of said tubular guide, the forward side of said guide having an elongate opening for delivery of carriers into the box. 95 100 105

3. Power control apparatus for use with a pneumatic tube line extending between two stations, said apparatus comprising a box having a normally closed aperture in its wall, a tubular guide extending from a point outside of the box to the inside thereof, said guide forming the terminal of a delivery tube, one side of the guide having an elongate opening within the box, and a deflector for directing carriers arriving through said opening toward the aperture in the box wall. 110 115

4. Power control apparatus for use with a pneumatic tube line extending between two stations, said apparatus comprising a box having an opening in its front wall, a door normally closing said opening, a vertical tubular guide disposed in the rear part of the box, said guide having an elongate opening within the box and tubular portions extending outwardly beyond the top and bottom walls respectively of the box, means uniting one of said outwardly extending portions of the guide to a delivery tube, 120 125 130

- means closing the other end of the guide, and deflector means within the guide for directing carriers outwardly through the elongate opening therein toward the door of the box.
5. Power control apparatus for use with a pneumatic tube line extending between two stations, said apparatus, comprising a box so connected to the delivery tube of the line as to receive carriers delivered therefrom, a detector within the box adapted to be held in abnormal position by a carrier in the box, a normally closed valve, connections for opening the valve when the detector is in abnormal position, and a whistle which sounds when the valve is open.
6. Power control apparatus for use with a pneumatic tube line extending between two stations, said apparatus comprising a box, tubular conduits connecting the interior of the box with the delivery and despatch tubes respectively of the pneumatic tube line, a movable cover normally closing the inlet to the conduit leading to the despatch tube, and means for opening the cover to admit a carrier.
7. Power control apparatus for use with a pneumatic tube line extending between two stations, said apparatus comprising a box having an opening in its wall, a door normally closing the opening, tubular conduits connecting the interior of the box with the delivery and despatch tubes respectively of the pneumatic tube line, a movable cover normally closing the inlet to the conduit leading to the despatch tube, and means so connecting the cover to the door of the box as to open the cover when the door is opened.
8. Power control apparatus for use with a pneumatic tube line extending between two stations, said apparatus comprising a box having an opening in its wall, a door normally closing the opening, tubular conduits connecting the interior of the box with the delivery and despatch tubes respectively of the pneumatic tube line, a movable cover normally closing the inlet to the conduit leading to the despatch tube, and means so connecting the cover to the door of the box as to open the cover when the door is opened, means providing a passage for air from the interior of the box to the despatch tube, and a valve controlling the flow of air through said passage.
9. Power control apparatus for use with a pneumatic tube line extending between two stations, said apparatus comprising a box having an opening in its wall, a door normally closing the opening, tubular conduits connecting the interior of the box with the delivery and despatch tubes respectively of the pneumatic tube line, a movable cover normally closing the inlet to the conduit leading to the despatch tube, means so connecting the cover to the door or the box as to open the cover when the door is opened, a casing having a valve chamber and valve therein, means connecting the valve chamber with the interior of the box and with the despatch tube respectively, and guard means preventing passage of carriers from the box into the valve chamber.
10. Power control apparatus for use with a pneumatic tube line extending between two stations, said apparatus comprising a box having an opening in its wall, a door normally closing the opening, tubular conduits connecting the interior of the box with the delivery and despatch tubes respectively of the pneumatic tube line, a movable cover normally closing the inlet to the conduit leading to the despatch tube, means so connecting the cover to the door of the box as to open the cover when the door is opened, a casing having a valve chamber and a valve therein, means connecting the valve chamber with the interior of the box and with the despatch tube respectively, means tending to open the valve, and means responsive to the presence of a predetermined number of carriers in a predetermined position for holding the valve closed.
11. A terminal for a pneumatic despatch system comprising a housing providing a substantially air-tight chamber, a door in the housing giving access to the chamber, and pneumatic tubes leading to and from the chamber, one of said tubes extending substantially vertically through the chamber and having an opening in its side wall through which a carrier passes from the tube to the chamber, the other tube opening into the chamber near the bottom of the latter, the chamber constituting a portion of the air circuit through the system.
12. Power control apparatus for use with a pneumatic tube line extending between two stations said apparatus comprising a box having an opening in its wall, a door normally closing the opening, tubular conduits connecting the interior of the box with the delivery and despatch tubes respectively of the pneumatic tube line, a false bottom in said box having an opening, through which carriers may pass, and which registers with the upper end of the conduit to the despatch tube, means normally preventing the passage of a carrier through the opening, and a connection between the preventing means and the door whereby the means is rendered inoperative when the door is opened.
13. Power control apparatus for use with a pneumatic tube line extending between two stations said apparatus comprising a box having an opening in its wall, a door normally closing the opening, tubular conduits connecting the interior of the box with the delivery and despatch tubes respectively of the pneumatic tube line, a false bot-

tom in said box having an opening, through which carriers may pass, and which registers with the upper end of the conduit to the despatch tube, and means connected to the door and normally preventing the passage of a carrier through the opening into the conduit.

14. Power control apparatus for use with a pneumatic tube line extending between two stations, said apparatus comprising a box having an opening in its wall, a door normally closing the opening, tubular conduits connecting the interior of the box with the delivery and despatch tubes respectively of the pneumatic tube line, and guard means connected to the door and normally obstructing the inlet to the conduit leading to the despatch tube whereby to prevent accidental redespatch of arriving carriers, said guard means being so associated with the door as no longer to obstruct the inlet when the door is opened.

Signed by me at Syracuse, New York this 2d day of October 1928.
